UNITED STATES PATENT OFFICE.

LESTER E. FULFORD, OF EDGEWOOD, RHODE ISLAND, ASSIGNOR TO FULFORD MFG. CO., OF PROVIDENCE, RHODE ISLAND, A CORPORATION OF RHODE ISLAND.

FASTENER DEVICE.

Application filed September 11, 1924. Serial No. 737,089.

To all whom it may concern:

Be it known that I, LESTER E. FULFORD, a citizen of the United States, residing at Edgewood, in the county of Providence and 5 State of Rhode Island, have invented certain new and useful Improvements in Fastener Devices, of which the following is a specification.

This invention relates to that type of fastener known as a glove fastener, but which may be employed for fastening together the adjacent portions of other articles; and an object of this invention is to provide an anvil member which is formed of a single piece 15 of sheet stock having the stock about its central opening turned inwardly to form a tapering guide for the entering end of the socket member when forced into the anvil.

A further object of this invention is to 20 form the anvil member of a single piece of sheet stock, the stock about the central, inner opening having a continuous and unbroken surface and when turned inwardly provides tapering guide for the entering end 25 of the socket member and also presents a smooth and unbroken surface to the glove stock or other material when bound in position by the flange of the socket element against the anvil, which does not cut or injure the clamped portion of the material.

With these and other objects in view, the invention consists of certain novel features of construction, as will be more fully described, and particularly pointed out in the 30 appended claim.

In the accompanying drawings:

Figure 1 is a sectional side elevation showing my improved construction of fastener with the flange of the socket member binding the stock against the continuous, inner, inturned, tapering wall of the anvil member.

Figure 2 is a detail illustrating the anvil member having its outer wall pierced and turned inwardly.

Figure 3 is a top view of the member illustrated in Figure 2.

Figure 4 shows the anvil complete with its inner wall turned inwardly to substantially the same central transverse plane as the edge of the outer wall.

Figure 5 shows a section of the outer cap member.

Figure 6 is a central section showing the 55 outer cap member as applied to the anvil

member and showing the socket element in dotted lines as guided into the anvil member by its tapering inner wall.

Figure 7 is an inner face view of the member shown in Figure 6.

Figure 8 is a sectional elevation of the socket member.

Figure 9 is a perspective view showing the reinforcing plate member which may be positioned to stiffen the wall of the cap 65 when made of celluloid.

It is found in practice of advantage to form the anvil member complete of a single piece of sheet metal and to so roll or turn the inner wall of this member inwardly as 70 to form a tapering guide for the socket member upon entering the anvil.

It is also found of advantage in the manufacture of these anvil members instead of notching the edges of the inner wall portion thereof, to form the same plain with a continuous unbroken surface which eliminates the necessity of cutting or serrating the blank and also facilitates and makes less expensive rapid manufacture of these devices in quantities as tools for such manufacturing are made with a continuous surface which will stand up much longer without repair and, therefore, a much greater production is obtained than from tools formed to provide a toothed or serrated edge on an anvil of this character; and the following is a detailed description of the present embodiment of my invention by which these 80 advantageous results may be accomplished: 85

With reference to the drawing, 10 designates an anvil member of the fastener device which as made in my improved form is constructed of sheet stock first in the form illustrated in Figure 2, with its outer wall 95 11 pierced as at 12 to form an enlarged opening therethrough and the wall about this opening is turned inwardly as at 13 to receive and turn outwardly the edge 14 of the socket element 15. The inner wall of the anvil member, as illustrated in Figure 4, is rolled inwardly as at 16 so that its inner edge 17 will practically extend to a central longitudinal plane through the anvil, and the opening 18 through this inner wall 100 is of a size somewhat greater than the opening 12 through the outer wall and is substantially the diameter of that of the shank of the socket element 15 thus providing an inwardly-tapering or funnel-shaped guide 105 110

for the inner edge 14 of the socket element 15 as it is forced into the anvil to cause its outer edge to be rolled outwardly and so fasten therein.

It is also found of advantage in the manufacture of anvils for fasteners of this character, to form the inner inturned wall with a continuous or unbroken surface for several reasons: first, the tools required for turning or rolling this edge inwardly where the surface is unbroken, are much less expensive to construct than those required for preparing and rolling a serrated edge inwardly, and second, the tools for rolling an unbroken edge will stand up much longer, do better work, and from such tools greater production can be obtained. Then again, by the forming of a smooth, continuous and unbroken inner engaging surface on this anvil, it will not cut into the stock of the work which, when formed of a thin kid, is of advantage as when forced onto a smooth surface the stock is not cut or weakened and so injured.

An outer cap 22 as illustrated in Figure 5, may be rolled over the anvil member to present an ornamental appearance and the same may be reinforced by plate 23, both the cap and the plate being shown in assembled position in Figure 1.

In assembling a fastener of my improved type the edge 14 of the socket member 15 is passed through an opening 19 in the stock 20 and is forced thereinto, the edge 14 being

turned outwardly into the anvil and the flange 21 of this socket is caused to bind the stock 20 against the surface of the anvil thus providing a hollow or socket portion into which the stud member (not shown) of the fastener device may be forced.

My improved form of fastener is very simple and practical in construction and effective in its operation.

The foregoing description is directed solely towards the construction illustrated, but I desire it to be understood that I reserve the privilege of resorting to all the mechanical changes to which the device is susceptible, the invention being defined and limited only by the terms of the appended claim.

I claim:

A socket member of a fastening device comprising an anvil member having a central opening through both its inner and outer walls, the opening through the inner wall being greater than that through the outer wall, a socket element closely fitted to and guided by the edge of the opening through the inner wall and engaging the inner surface of the wall of the opening through the outer wall and spread thereby in being forced to operating position to lock said element in engagement with said anvil.

In testimony whereof I affix my signature.

LESTER E. FULFORD.
